Fig. 1

Fig. 3

Fig. 2

Fig. 4

FIG. 1 is a perspective view of a tire embodying our new design, it being understood that the full line portion is repeated throughout the circumference of the tire, shown by means of broken lines;

FIG. 2 is an enlarged transverse sectional view of the tire shown in FIG. 1;

FIG. 3 is an enlarged fragmentary elevational view of the full line portion shown in FIG. 1; and

FIG. 4 is an enlarged fragmentary perspective view, partly in section, of the full line portion shown in FIG. 3.

The dominant features of our design reside in those portions shown in full lines in the drawings.

We claim:

The ornamental design for a tire, substantially as shown and described.
